United States Patent

Des. 237,617
Patented Nov. 11, 1975

237,617

PORTABLE SINK

Lawrie G. McIntosh, Mississauga, Ontario, Canada, assignor to Reliance Products Ltd., Winnipeg, Manitoba, Canada

Filed Nov. 2, 1973, Ser. No. 412,187

Term of patent 14 years

Int. Cl. D23—02

U.S. Cl. D23—58

FIG. 2

FIG. 1

FIG. 3

FIG. 4

FIG. 5

FIG. 6

FIG. 1 is a top plan view of a portable sink showing my new design; with lid being shown in an open position.

FIG. 2 is another top plan view thereof, with the lid being shown in the closed position.

FIG. 3 is a front elevational view of FIG. 2.

FIG. 4 is an elevational view taken from one side of FIG. 2, the opposite side being a mirror image of the side shown.

FIG. 5 is a rear elevational view of FIG. 2.

FIG. 6 is a bottom plan view of FIG. 2.

The opposite side view is the same as FIG. 4.

I claim:

The ornamental design for a portable sink, as shown and described.
